UNITED STATES PATENT OFFICE.

SAMUEL SEGAL, OF NEW YORK, N. Y., ASSIGNOR TO SEGAL LOCK & HARDWARE CO., INC., OF NEW YORK, N. Y., A CORPORATION OF NEW YORK.

LOCK.

Application filed July 22, 1926. Serial No. 124,152.

This invention relates to a lock of improved construction, and specifically, a lock of the cylinder type.

It is an object of the invention to provide a lock in which hand-fitting operation will be reduced to a minimum, and in which the parts will be relatively few in number and simple in construction, these parts being provided by automatic machinery and assembled into a perfectly functioning lock by relatively unskilled labor, thereby reducing construction costs.

It is a further object of the invention to provide a lock the mechanism of which may be operated with a minimum of resistance, and in which any wear may be readily compensated for so that the parts will not jam or grip the key; the parts being prevented from accidental relative movement, and when necessary, being readily disassembled.

Other objects of the invention will in part be obvious and will in part appear herein-after.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawings, in which:

Figure 1 is a sectional view of a cylinder lock embodying one form of construction within the terms of the present invention; and

Fig. 2 is a rear end view thereof.

In these views the numeral 5 indicates the cylinder body, which is formed with the usual longitudinally-extending bore, within which the lock plug 6 is rotatably mounted, movement of the latter in one direction being prevented by means of an enlarged head portion 7 seating within a correspondingly enlarged portion of the cylinder bore.

It is here to be understood that the plug is formed with a key slot and carries a series of tumblers mounted one within each of bores formed in the body of the plug; these tumblers being of such length as to provide a proper lock permutation and cooperating with spring-pressed pins carried by the cyl-

inder within bores extending transversely of its body.

Contrary to conventional construction, in which the plug has its rear end terminating in substantially the same plane as the rear face of the cylinder, the plug in the present instance is extended materially beyond this plane and is formed with a screw-thread 8, which begins at a point short of the plane of the rear face of the cylinder, and preferably terminates at a point spaced from the outer end of the plug, the latter being thus provided with a smooth face 9 at this point, which face has a diameter less than the major portion of the plug body and is interrupted by a notch 10, which may, if desired, form a continuation of the key slot.

Adjacent its outer end the plug is formed with a transversely-extending bore, which intersects the notch 10, and mounted within this bore is a pin 11, the outer end of which normally projects beyond the side face of the plug, this being assured, if desired, by the use of a spring 12 mounted within this bore and interposed between the base of the same and the pin end.

A collar or washer 13 is provided with an internal thread corresponding to the thread 8, and the body of this element is formed with a crown or rearwardly-extending flange portion 14 interrupted by a series of notches 15, which are of a size insufficient to accommodate the body of the pin 11, but readily accommodate the reduced end portion 16 thereof.

It is obvious that a plug of this nature may be manufactured by automatic machinery, as may also the collar or washer and the pin. With the parts thus provided an operator may assemble the same by simply inserting the plug into the bore of the cylinder until the head 7 of the former seats firmly within the enlarged portion at the outer end of the latter. In such position of the parts the rear end of the plug obviously will extend beyond the rear wall of the cylinder, and at this time the operator may associate the tail-piece 17 with the plug by simply aligning the opening of the former with the transverse bore which accommodates the pin 11, and thereupon inserting the pin to prevent material relative movement of the plug and tail-piece. If the latter is caused to engage the pin, this element will be retained

against movement incident to its frictional engagement with the tail-piece, and, as a consequence, the collar or washer 13 may be applied to the plug until the threads of the former engage with the threads of the latter, and this movement is continued to a point at which the plug is held adequately from any end play, without the parts binding, however. In such position, and upon the release of the tail-piece, the reduced end portion 16 of the pin 11 will be projected to extend through the adjacent notch formed in the collar or washer, and thus the latter is prevented from movement with respect to the plug parts; it being thus understood that the pin, in addition to anchoring the tail-piece in place, performs a similar service for the washer or collar.

The purpose of having the threads terminate short of the plug end will at this time be clear, in that by this construction the work of assemblage is facilitated.

Obviously, the plug may be turned freely by the use of a proper key, and if after long periods of use the plug should wear so that a slight end play will be apparent, this may be readily remedied by simply turning the element 13 with respect to the plug body to the extent of one notch after the retraction of the pin 11. In order to illustrate the micrometer adjustment provided by such turning, it will be noted that if the threads 8 are 40 to the inch, and, as has been shown, if eight equally-spaced notches are provided in the rearwardly-extending flange portion 14, a turning of the collar or washer a distance of one inch will provide a .003" adjustment.

It will be apparent that by a construction of this nature all hand filing, fitting, delicate machining and adjusting is eliminated, and, if necessary, the plug may readily be removed from the cylinder without the use of tools. Furthermore, with such a construction, end play on the part of the plug will come into existence only through wear of the parts and not by a loosening of the same.

Thus, among others, the objects of this invention have been accomplished, and since certain changes may be made in the above construction, and different embodiments of the invention could be made, without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A lock, including, in combination, a bored cylinder, a plug extending into said cylinder and beyond the same, adjustable means bearing against the rear face of the cylinder and secured to the extended portion of said plug for retaining the latter in position and readily releasable means for normally preventing movement of said first named means with respect to said plug.

2. A lock, including, in combination, a bored cylinder, a plug extending into said cylinder and beyond the same, means bearing against the rear face of the cylinder and secured to the extended portion of the plug for retaining the same in proper position, and means whereby the position of said last-named means may be adjusted.

3. A lock, including, in combination, a bored cylinder, a plug extending into said cylinder and beyond the same, means bearing against the rear face of the cylinder and secured to the extended portion of the plug for retaining the same in proper position, means whereby the position of said last-named means may be adjusted, and locking means therefor.

4. A lock, including, in combination, a bored cylinder, a plug rotatable within said bore and extending beyond the same, means movably mounted upon the extended portion of said plug and acting against the rear face of the cylinder to maintain the parts in proper position and means for normally retaining said last named means immovable with respect to said plug.

5. A lock, including, in combination, a bored cylinder, a plug within said bore and extending beyond the same, the extended portion of said plug being formed with screw threads, a nut mounted upon said threads and acting against the rear face of the cylinder to maintain the plug in position, and readily releasable means for locking said nut against movement with respect to said plug.

6. A lock, including, in combination, a bored cylinder, a plug within said bore and extending beyond the same, the extended portion of said plug being formed with screw threads, a nut mounted upon said screw threads and bearing against the rear face of said cylinder for adjusting the same, and a tail-piece connected with the extended portion of said plug.

7. A lock, including, in combination, a bored cylinder, a plug within said bore and extending beyond the same, the extended portion of said plug being formed with screw threads, a nut mounted upon said screw threads and bearing against the rear face of said cylinder for adjusting the same, a tail-piece, and means associated with said

plug for locking said nut against movement and anchoring said tail-piece to said plug.

8. A lock, including, in combination, a bored cylinder, a plug within said bore and 5 extending beyond the same, the extended portion of said plug being formed with screw threads, a nut mounted upon said screw threads and bearing against the rear face of said cylinder, a tail-piece, and a pin 10 carried by said plug and extending through an opening in said tail-piece to anchor the same to the plug.

9. A lock, including, in combination, a bored cylinder, a plug within said bore and 15 extending beyond the same, the extended portion of said plug being formed with screw threads, a nut mounted upon said screw threads and bearing against the rear face of said cylinder, a tail-piece, and a pin 20 carried by said plug and extending through an opening in said tail-piece to anchor the same to the plug, said pin engaging said nut to normally lock the same against movement.

25 10. A lock, including, in combination, a bored cylinder, a plug within said bore and extending beyond the same, the extended portion of said plug being formed with screw threads, a nut mounted upon said 30 screw threads and bearing against the rear face of said cylinder, a tail-piece, and a spring-pressed pin associated with said plug and anchoring said tail-piece against material movement with respect thereto, said 35 pin bearing against said nut to prevent movement of the same with respect to the plug.

11. A lock, including, in combination, a bored cylinder, a plug within said bore and 40 extending beyond the same, said extended portion being formed with screw threads, a nut mounted thereon and engaging the rear face of the cylinder to prevent material movement of the plug with respect thereto, 45 and a pin carried by said plug, said nut

being formed to receive one of the ends of said pin whereby to lock the former with respect to the plug.

12. A lock, including, in combination, a bored cylinder, a plug within said bore and 50 extending beyond the same, said extended portion being formed with screw threads, a nut mounted thereon and engaging the rear face of the cylinder to prevent material movement of the plug with respect thereto, 55 and a pin carried by said plug, said nut being formed with a series of recesses engaged by one of the ends of the pin to normally prevent movement of the nut and plug.

60 13. A lock, including, in combination, a bored cylinder, a plug within said bore and extending beyond the same, the extended portion of said plug being formed with screw threads terminating at a point short of the rear end thereof, and means mounted upon said screw threads and acting against the rear face of the cylinder for preventing axial movement of the plug with respect thereto.

70 14. A lock, including, in combination, a bored cylinder, a plug within said bore and extending beyond the same, said extended portion being formed with a notch and a transversely-extending bore, screw threads 75 upon the outer face of said plug, a nut mounted upon said threads and acting against the rear face of the cylinder to prevent axial movement of said plug with respect thereto, a tail-piece extending into 80 said notch and formed with an opening in line with said transverse bore, and a pin extending within said bore to anchor said tail-piece against material movement with respect to said plug and engaging the nut 85 to lock the same against movement with respect to the latter.

In testimony whereof I affix my signature.

SAMUEL SEGAL.
